Fig. 2.

A technical drawing of a rectangular frame. The frame is composed of two concentric rectangles. A circular hole is located in the center of the inner rectangle. The outer edge of the frame features a decorative border. The drawing is annotated with several numbers: '18' is on the left side of the outer frame; '19' is at the bottom right corner of the inner frame; '2a' is at the top right corner of the outer frame; '2b' is at the bottom right corner of the outer frame; and '3' is positioned to the right of the circular hole. A large, handwritten label 'H. B. %' is written across the top of the frame.

UNITED STATES PATENT OFFICE.

GEORGE W. CHANTIGNEY AND JOSEPH P. MORENCY, OF MONTREAL, QUEBEC, CANADA.

BUILDING CONSTRUCTION.

No. 879,520.

Specification of Letters Patent.

Patented Feb. 18, 1908.

Application filed November 27, 1905. Serial No. 289,209.

To all whom it may concern:

Be it known that we, GEORGE W. CHANTIGNEY and JOSEPH P. MORENCY, subjects of the King of Great Britain, residing at the 5 city and district of Montreal, in the Province of Quebec, Canada, have invented certain new and useful Improvements in Building Construction; and we do hereby declare that the following is a full, clear, and exact description 10 of the invention, such as will enable others skilled in the art to which it appertains to make and use the same.

Our invention relates to building construction; the object of our invention is to provide 15 a construction having a continuous double wall provided with a continuous air space around the entire structure; a further object is to provide means for ventilating each room; a further object is to provide 20 means for draining the moisture from the dead air space in the walls of the structure; and, our invention consists of the construction, combination and arrangement of parts as herein illustrated, described and claimed.

25 In the accompanying drawings forming part of this application, we have illustrated one form of embodiment of our invention, in which drawings similar reference characters designate corresponding parts, and in which:

30 Figure 1 is a vertical section through a building constructed in accordance with this invention; Fig. 2 is a vertical section through a similar building, taken in a different plane to Fig. 1, that is taken through the 35 window openings; Fig. 3 is a horizontal section on line 3—3 of Fig. 2; Fig. 4 is a vertical section through the space between two windows in the side wall; Fig. 5 is a horizontal section taken through the junction of 40 a partition and a side wall; Fig. 6 is a horizontal section taken through the corner of the walls, showing the reinforcing members; Fig. 7 is a horizontal section through a corner showing the construction of the conduit; 45 Fig. 8 is a vertical section through a floor joist, showing the reinforcing member; and, Fig. 9 is a perspective view of a reinforcing member used in the side walls.

Referring to the drawings, 1 designates a 50 base or foundation formed of plastic material. Disposed on the foundation and formed integral therewith, is a wall 2, extending to the ground line of the structure. Formed continuous with the wall 2 from the ground 55 line upward, are the side walls 2^a, 2^b, having a dead air space 3 between the same. Dis-

posed on the foundation 1 and extending upwardly to the roof, is a solid partition wall 4, also formed of plastic material. The joists 5 are formed from plastic material, and reinforced with a suitable beam 6. The walls 2^a, 2^b are reinforced and held together by the reinforcing members 7, having angular ends 7^a. Where the partitions 4 and side walls 2^b are joined together, they are reinforced 65 by the horizontally disposed T-irons 8.

As best shown in Fig. 4, the walls 2^a and 2^b are connected by the webs 9, between the windows. The vertical webs 9 are provided with openings 10 to permit the circulation of 70 air beneath the windows.

The walls 2^b adjacent the ceiling in each apartment formed in this construction, are provided with openings 11, and adjacent the floor in each apartment are provided with 75 openings 12, so that each apartment may be ventilated by means of these openings, which may be closed by any suitable form of ventilating apparatus.

Adjacent their upper ends, the inner walls 80 2^b are provided with ducts 13, and the walls 2^a, 2^b are covered by a coping 14. A suitable roof 15 of ordinary construction is placed on the building below the coping 14.

The walls 2^b are provided with ducts 16, 85 adjacent their lower ends, which ducts are inclined downward, so that any moisture which accumulates in the dead air space 3 will be drained into the cellar, from whence it may be conducted to any suitable place of 90 deposit.

The corners of the walls 2^a, 2^b are reinforced by means of the angle irons 17 (Fig. 6), and the corners of the walls 2^b are provided with smoke flues 18, formed in enlargements 19, which enlargements are integral with and formed from the same material as the walls 2^b.

The walls 2^a, 2^b, are provided with suitable window and door openings 20, and the 100 solid partitions 4 are provided with door openings 21.

Having thus fully described our invention, what we claim as new and desire to secure by Letters Patent, is:—

A building comprising an imperforate outer wall, an inner wall spaced therefrom to provide a continuous intervening air space, said inner wall being provided at different levels with ventilating openings communicating with the interior of the building, and ventilating ducts at its top, a roof supported

on said inner wall at a distance below said ducts, and a coping extending across the tops of said inner and outer walls and projecting over said inner wall, whereby said roof and coping efficiently shield said ventilating ducts from the entrance of extraneous matter, substantially as described.

In witness whereof we have hereunto set our hands in the presence of two witnesses.

GEORGE W. CHANTIGNEY.
JOSEPH P. MORENCY.
